ARCHITECTURAL PANEL

Roland R. Sahm, Palos Verdes Estates, Calif., assignor to Elixir Industries, Gardena, Calif.

Filed Aug. 31, 1970, Ser. No. 24,789

Term of patent 14 years

Int. Cl. D25—01

U.S. Cl. D54—2

FIG. 1 is a front elevational view of an architectural panel showing my new design; and

FIG. 2 is a fragmentary sectional view on an enlarged scale taken between the arrows 2—2 of FIG. 1.

I claim:

The ornamental design for an architectural panel, as shown.
